UNITED STATES PATENT OFFICE.

FERNANDO CASABLANCAS, OF SABADELL, SPAIN.

MECHANISM FOR DRAWING ROVINGS OF WOOL AND OTHER TEXTILE FIBERS.

1,079,837.

Specification of Letters Patent. Patented Nov. 25, 1913.

Application filed May 14, 1912. Serial No. 697,185.

To all whom it may concern:

Be it known that I, FERNANDO CASABLANCAS, a subject of the King of Spain, residing at Sabadell, Barcelona, Spain, have invented 5 certain new and useful Improvements in Mechanism for Drawing Rovings of Wool and other Textile Fibers; and I do hereby declare the following to be a full, clear, and exact description of the invention, such as 10 will enable others skilled in the art to which it appertains to make and use the same.

This invention relates to mechanism for drawing rovings of wool and other textile fibers and consists in the constructions, arrangements, and combinations of parts hereinafter described and claimed.

It is an object of my invention to provide a device of the above character having improved drawing means and so located with 20 reference to the other separate mechanisms on the roving frame, with which it operates in combination, as to provide drawing through a relatively extended length of the twisted roving in short drafts at high 25 speeds.

In describing my invention in detail reference will be had to the accompanying drawings wherein like symbols refer to like or corresponding parts throughout the several 30 views, and in which—

Figure 1 is a diagrammatic view of the various mechanisms of the improved roving frame. Fig. 2 is a sectional view of my improved drawing mechanism. Fig. 3 is an 35 elevation of the same. Fig. 4 is a top plan view of the same. Fig. 5 is a detail view of the drawing rollers; and Fig. 6 is an enlarged detail of one of the rollers.

Referring more particularly to the drawing 40 ing, 1 designates the feeding rollers for receiving the sliver or roving 2 and passing the same on through the flier or twisting tube 3 to the delivery roller 4, whence the roving is carried to the bobbin on the spinning 45 dle as illustrated and as will be understood.

In accordance with the principle of my invention the drawing rollers, hereinafter to be described in detail, are located between the feeding and delivery rollers and in advance 50 of the flier 3. This arrangement of mechanisms permits a relatively extended length of the roving to be operated upon by the drawing rollers and leaves a space in rear of the drawing rollers to accommodate 55 the slack created in the roving by the draft.

The drawing rollers consist of sleeves 6

and 10 mounted respectively on parallel shafts 5 and 9 which are rotated in opposite direction by any suitable means. Each of the sleeves 6 and 10 is provided with a plurality of sectors 7 and 11 projecting preferably in diametrically opposite directions, the sectors being narrow and having a minimum surface contact. The sleeves 6 and 10 are adjustable radially so as to vary the contact surfaces as hereinafter explained, but have sufficient frictional engagement with their shafts 5 and 9 to rotate with the same. The sectors are preferably faced with metal; however, they may be provided with dovetailed slots 21, as shown in Fig. 6, for the reception of the leather or other tips 8.

Supported by suitable standards adjacent the shaft 9 is a shaft 18 to which is hinged opposite sections 13 and 14 of a two-part casing for inclosing the drawing rollers, from the lower section 13 of which projects a slotted arm 15 engaged by a bolt 16 for supporting the casing from the framework 17. The casing is dust-excluding and receives accumulations of nap which adheres to the sectors from contact with the roving and is removed from the same by the brushes 12.

Alining slots 19 are provided in each section 13 and 14 of the casing and open through one side of the same to permit the ready insertion of the roving, which, in the event of breakage, must be tied and replaced. A bow of wire 20 is attached at 90 one end to the upper section 14 of the casing and bridges the slot 19 so as to provide a surface over which the roving may run and prevent the same entering between the drawing rollers. This arrangement is utilized to 95 advantage when, after a breakage, the roving is tied and it is not desired to subject the weakened portion to the severe action of the drawing rollers. The roving is permitted to run on the bow 20 and drawn by 100 the delivery rollers 4, until the weakened portion being carried past the latter, the operator may, by a movement of the finger, cause the roving to be disengaged from the bow, whereupon, due to the inclination of 105 the casing and guided by the bow, the same will enter the slot 19 and resume its position between the drawing rollers.

In the operation of my improved roving frame the delivery rollers 4 are to have a 110 speed proportionately greater than the feeding rollers 1 whereby to effect drawing in the

event of breakage as above described, and also not to permit an excess of slack between the flier 3 and the drawing rollers. The latter are to be operated at a high rate of speed and exert a severe draft on the roving, but as the draft is effected over a relatively extended length, and as the contact surfaces of the sectors are very small and having wide circumferential spaces between them 10 allow longer intervals for the twisting, the severe action is unproductive of an increased number of breaks, and the strains produced during the drawing operation are taken up by the elasticity of the roving 15 which is permitted by the slack constantly present in rear of the drawing rollers due to the inferior speed of the delivery rollers.

I have described preferred and satisfactory constructions but desire it to be understood that slight changes may be resorted to without departing from the spirit of my invention provided such changes fall within the scope of the appended claims.

I claim:

25 1. In a roving frame, feeding rollers, delivery rollers operating at a relatively greater speed than said feeding rollers, a flier for imparting the required twist to the roving, and drawing rollers operating at a 30 relatively greater speed than said delivery rollers and located between said feeding and delivery rollers in proximity to the latter providing an extended length of roving subjected to drawing, and a relatively short 35 space between said drawing and delivery rollers to accommodate the slack.

2. In a roving frame, feeding rollers, delivery rollers operating at a relatively greater speed than said feeding rollers, a flier for 40 imparting the required twist to the roving, and drawing rollers operating at a relatively greater speed than said delivery rollers and provided with diametrically opposed sectors of minimum surface contact engaging with 45 the roving, said drawing rollers being located between said feeding and delivery rollers in proximity to the latter providing an extended length of roving subjected to drawing and a relatively short space between said 50 drawing and delivery rollers to accommodate the slack.

3. In a roving frame, feeding and deliv-

ery rollers, a flier for imparting the required twist to the roving, and drawing rollers provided with adjustable sectors for varying 55 the duration of contact with the roving.

4. In a roving frame, feeding and delivery rollers, a flier for imparting the required twist to the roving, and drawing mechanism located between said feeding and delivery 60 rollers and comprising a pair of oppositely rotating parallel shafts, adjustable sleeves mounted to turn with said shafts, and a plurality of coöperating sectors projecting from said sleeves and engaging with the roving to 65 draw the same.

5. In a roving frame, feeding rollers, delivery rollers operating at a relatively greater speed than said feeding rollers, a flier for 70 imparting the required twist to the roving, and drawing mechanism operating at a relatively greater speed than said delivery rollers and located between said feeding and delivery rollers in proximity to the latter providing an extended length of roving subject to drawing and a relatively short space 75 between said drawing and delivery rollers to accommodate the slack, said mechanism comprising a pair of oppositely rotating parallel shafts, adjustable sleeves mounted to turn with said shafts, and a plurality of coöperating sectors projecting from said sleeves and engaging with the roving to draw the same.

6. In a roving frame, feeding and delivery rollers, a flier for imparting the required twist to the roving, drawing mechanism located between said feeding and delivery rollers and comprising a pair of oppositely rotating parallel shafts, adjustable sleeves 80 mounted to turn with said shafts, and a plurality of coöperating sectors on said sleeves for engaging the roving, a casing for housing said mechanism provided with a slot 85 adapted to admit the roving, and a bow 90 supported at one end on the casing and bridging the slot.

In testimony whereof, I affix my signature, in presence of two witnesses.

FERNANDO CASABLANCAS.
